[57] CLAIM

The ornamental design for a power supply housing, as shown and described.

DESCRIPTION

FIG. 1 is a right perspective view of the power supply housing of the present invention;

FIG. 2 is a rear perspective view thereof;

FIG. 3 is a front elevational view thereof;

FIG. 4 is a rear elevational view thereof;

FIG. 5 is a right elevational view thereof;

FIG. 6 is a left elevational view thereof;

FIG. 7 is a top plan view thereof; and,

FIG. 8 is a bottom plan view thereof.

The phantom lining throughout the drawing figures is included for the purpose of illustrating the power supply housing only and forms no part of the claimed design.
